UNITED STATES PATENT OFFICE.

JESSE W. ALEXANDER, OF BIRMINGHAM, ALABAMA.

CONCRETE-WALL MOLD.

1,142,388.

Specification of Letters Patent.

Patented June 8, 1915.

Application filed April 27, 1914. Serial No. 834,560.

To all whom it may concern:

Be it known that I, JESSE W. ALEXANDER, a citizen of the United States, residing at Birmingham, in the county of Jefferson and State of Alabama, have invented certain new and useful Improvements in Concrete-Wall Molds, of which the following is a specification.

My present invention relates to improvements in apparatus used in constructing cement or concrete walls, and particularly to that form of such apparatus which comprises adjustable molds between which the concrete is poured when in plastic condition.

The especial objects of my improvement are:—(a) The production of form molds of simple and inexpensive construction; (b) the provision of means whereby the plates of which the molds are chiefly formed may be brought into operative positions quickly, accurately and with the minimum exertion of manual effort; (c) a strong and durable construction both in the matter of the individual members and in the manner of their assemblage into the complete apparatus.

Having the foregoing special objects, and others of general utility and novelty in view, I have invented the apparatus of which a preferred adaptation is illustrated in the accompanying drawing, in which:—

Figure 1 is an elevational view of a set of frames and complementary parts, which constitute a single unit of my invention, the same being shown in connection with a section of hollow or spaced concrete walls; Fig. 2 is a sectional and plan detail on the line 2—2 of Fig. 1; Fig. 3 is a detail in plan view of the plate operating lever and adjacent parts, and—Fig. 4 is a view partly in section and partly in plan, on the line 4—4 of Fig. 1.

In carrying out my invention, I preferably employ a plurality of vertical standards, which may be I-beams, channel or L-bars, or other suitable forms, and these are spaced apart six or eight feet and supported or secured at their ends in any approved manner. I have shown in the accompanying drawings, a special form of I-beam, designated by the reference numeral 3, as peculiarly adapted to the members which make up complete apparatus. These beams are erected on opposite sides of the wall under construction, at the proper distance from the structure to accommodate the mold-plates and their complementary members.

4—4 represent flat metal bars which are arranged in pairs and spaced apart to receive between them the beams 3, with which they stand parallel. Each bar 4 has mounted near its ends, grooved wheels 5, 5, which are adapted to ride on the adjacent flanges of the I-beams. Near their upper ends, the four bars 4 which make up a frame unit are rigidly connected by a horizontal bar 6. 60 Each pair of bars 4, has bolted thereto horizontally arranged angle-bars 7—8, which hold the bars in true parallel relation.

9 represents one of the mold plates employed in my apparatus. This is made of sheet metal in any size desired, at its upper edge is flanged over as at 9^a, and along its lower edge is provided with an angle-plate 9^b, which serves to stiffen the plate, and properly connect it with the members by 75 which it is supported.

10, 10^a, represent respectively the horizontal and vertical portions of an angular frame preferably formed of channel-iron. T-bars 10^b are bolted at the upper corners 80 of the frame 10, and are engaged by the flange 9^a to support the plate 9, in vertical position, the angle-plate 9^b, resting against the lower corner of the frame 10.

11 represents a hinge-rod, portions of 85 which are squared, as at 11^a, 11^b. The ends of this rod are journaled in socket-plates 12 which are bolted to one of the bars 4. On the squared portion 11^b is mounted a handle 13 by which the rod is turned in its sockets. On the squared portions 11^a, are mounted horizontally extending arms 14, with which are pivotally connected one end 90 of links 15, the other ends of which are pivotally connected with brackets 16 on the frame member 10^a, thus forming a double hinge connection between the rod 11 and said frame 10, 10^a.

While I have shown the various parts that make the complete structure, at the left hand side of the drawing only, it will be understood that the parts designated 7 to 16, respectively are duplicated, and taken together provide the forms for the outer face of the walls under construction.

17, 18, represent respectively, the core-plates of my improved apparatus, the same corresponding in size and material with the plates 9. The core-plates are cut and bent over at their upper edges to provide hang- 105 ers which embrace bolts 19, 20, which are 110 slidably arranged in slots 6^a, in the bar 6,

and in a brace 6^b, which is bolted to the bar 6 (Fig. 3).

Angle-bars 21, 22, 27 and 28, are bolted to the opposed sides of the plates 17, 18. A rod 23 is journaled in the bars 21, 22, and has a lever 24 on its upper end. Portions of the rod 23, are squared and arranged on such portions, are links 25, 26, the free ends of which are slidably and pivotally connected 10 with slots 27, (Fig. 4) in the bars 27, 28. In Fig. 4, I have shown the position of the link 25 when the core-plates are in their expanded position, and in Fig. 3, I have shown the lever 24 in the position it assumes when 15 the plates are retracted, but the latter are shown in their expanded relation.

29 represents gravity levers or dogs which are pivoted on the bars 4, in position so that the pointed end of the dog will engage 20 the web of bar 3, and thus support the apparatus in whatever position it may have been raised to. As many of these dogs will be provided as may be necessary for the support of each unit.

25 In the use of my improved apparatus, suitable beams 3 will be erected in a manner appropriate to provide vertical standards of sufficient rigidity and height to build a substantial section of wall. The adjustable or mobile apparatus in as many 30 units or sections made up as above described, will be arranged at the base of the beams 3, and the outer face mold-plates 9, will be moved to the desired relative position 35 by operating the levers 13. The core-plates 17—18, will then be expanded to the extent required to make concrete walls of the desired thickness, and the concrete will be poured between the mold walls composed of 40 plates 9 on the outer face and plates 17—18 respectively on the inner face. When the concrete has set sufficiently to permit the removal of the plates, the apparatus will be raised by any suitable means, and will be 45 held in such position by the dogs 29 as above set forth.

It is obvious that I may duplicate the arrangement and connections of the operating rods 11, 23, so that they will support the

plates 9, 17, 18, at as many points as the 50 character of the work may require.

It is also obvious that the construction disclosed provides for the proper alinement of the plates and their maintenance, to effect a wall of true dimensions without the use 55 of ties, while facilitating the quick and easy adjustment of the plates in planes at right angles to the face of the walls under construction.

What I claim:—

1. In an apparatus of the class described, a vertically adjustable supporting frame, outer face mold-plates carried thereby, means adjustably connecting said plates with said frame comprising an angular 65 frame, a rock-shaft rotatably mounted on said supporting frame and parallel hinge connections between said rod and said angular frame, substantially parallel core-plates, adjustably carried by said frame, a vertical 70 rock-shaft disposed between said core-plates and journaled on one of said core-plates, and links operatively connecting said vertical rock-shaft to the other of said core-plates: 75

2. In an apparatus of the class described, a vertically adjustable supporting frame, outer face mold-plates, means adjustably connecting said plates with said frame, said means comprising an angular frame upon 80 which said plates are detachably hung, a rod rotatably mounted on said supporting frame, and parallel links pivotally connected with said rod and angular frame, in combination with core-plates arranged parallel 85 with said outer face mold-plates, and connected with said supporting frame, and means for adjusting said core-plates, said means comprising a rod rotatably connected with one of said plates and links on said 90 rod having pivotal and slidable connections with the opposite core plate.

In testimony whereof I affix my signature in the presence of two witnesses.

JESSE W. ALEXANDER.
